CLAIM

The ornamental design for a lid, as shown and described herein.

DESCRIPTION

FIG. 1 is a first perspective view of a lid.

FIG. 2 is a second perspective view of the lid of FIG. 1 taken from the opposite side.

FIG. 3 is a third perspective view of the lid of FIG. 1 taken from the bottom.

FIG. 4 is a first side view of the lid of FIG. 1.

FIG. 5 is a second side view of the lid of FIG. 1 taken from the opposite side of FIG. 4.

FIG. 6 is a front view of the lid of FIG. 1.

FIG. 7 is a back view of the lid of FIG. 1.

FIG. 8 is a top view of the lid of FIG. 1.

FIG. 9 is a bottom view of the lid of FIG. 1; and,

FIG. 10 is a cross-sectional side view of the lid of FIG. 1, wherein the cross-section is taken along line 10-10 of FIG. 8.

The broken lines disclosing the environment related to the claimed design and form no part of the claimed design.

1 Claim, 8 Drawing Sheets(56)
